ELECTROCAPILLARY DEVICE

Application filed March 5, 1929, Serial No. 344,280, and in Great Britain August 25, 1928.

It is known that electrocapillary phenomena, discovered by Lippmann reside in the fact that the variation of potential difference between two bodies such, for example, as mercury and an acid solution, modifies the characteristics of the contacting surface and particularly the value of the capillary constant. Conversely, a variation of the capillary constant resulting from a deformation of the contacting surface produces a corresponding variation in the potential difference of conduct.

The present invention relates to various apparatus, whose mode of operation is based on the above recalled phenomena and whose aim is either to transform, as in the case of microphones, sound waves into electric currents, or to transform, as in the case of telephone receivers and loud speakers, electric currents into sound waves, or else to detect electric oscillations.

From a historical point of view, it must be recalled that the principle of the invention has already been indicated in the work of Comte du Moncel "Le téléphone, le microphone, et le phonographe", 1878, which was translated into English in 1879 (see page 110/113 of this translation).

Various forms of embodiment of the apparatus according to the invention have been represented, diagrammatically and merely by way of example on the appended drawing in which:

Fig. 1 is a sectional elevation of one form of construction of the apparatus.

Fig. 2 shows another form of embodiment.

Fig. 3 shows the connection in parallel of various elements similar to that of Fig. 2.

Figs. 4 and 5 show different constructional forms.

Fig. 6 shows the series connection of several elements similar to that of Fig. 1.

Fig. 1 represents an embodiment of an electrocapillary microphone. A capillary tube 1, whose inner section increases, towards the upper opening, according to an exponential law, dips into the mercury 2 after having been filled with an electrolyte 3 (salt water, acidulated water, or the like) covered in its turn with a layer of oil 4 to prevent evaporation.

A conductor 5 is led from the electrolyte and a conductor 6 from the mercury.

The conductors 5 and 6, of acid proof metal, are connected to the primary of a transformer through the intermediary, or not, of a potentiometer.

It will be easily understood that the deformations of the upper surface of the electrolyte, which result from the action of sound waves, produce corresponding deformations in the contacting surface of the meniscus 7 of the capillary tube, and, consequently, corresponding variations of potential difference between the conductors 5 and 6.

A very satisfactory sensitiveness and quality of reproduction is obtained with a tube whose inner diameter (d), measured at a height (h), calculated from the lower end when considered as a basis line, is a function of this height, which may approximately be rendered as:

$$d = d_0 e^{ch}$$

with $d_0 = 0.7$ mms.

$c = 0.05$ (h being calculated in mms.) ;

h (total) = 50 mms.

By making use only of salt water, of 5% (by weight), as electrolyte, it will be found that the impedance is of the order 1.600 ohms for a frequency of 800.

Fig. 2 represents a further embodiment of the invention in which the contact with the electrolyte is obtained by an acid proof metallic surface of large area in order to reduce the impedance of the double surface "electrolyte-contact."

The meniscus is situated inside a calibrated capillary glass tube 8, connected to a metallic tube 9 (of nickel, iron nickel alloy, iron-nickel-chromium or the like . . .) which is unattackable by the electrolyte 10 and which forms a cavity having a section which diverges towards the upper opening, substantially in accordance with an exponential law. The metallic portion is of course insulated on the outside and eventually provided with a depth regulator allowing the position of the meniscus to be suitably fixed thereby reducing the electric losses of the liquid col-

an. For setting purposes, it will be sufficient, for example, to mount the tube 9, in such a manner as to be in slight frictional sliding contact within the stopper 14, so that the vertical tube may be moved. The stopper 14 is furthermore provided with a hole

This device, of which several similar units may be reproduced, lends itself to the connection of several elements in series or in parallel in which the elemental impedances could be equal, and the variations in the elemental electric voltages should be equal and in phase.

Fig. 3 represents an assembly of seven elements mounted in parallel, such as A, B, C, etc., dipping in the mercury M; each element essentially comprises a metallic portion and a glass portion similar to those of the device according to Fig. 2. The various tubes communicate with each other at their upper end in order to equalize the levels. In Fig. 6 is shown the connection in series of several electrocapillary elements, similar to the one Fig. 1.

In the preceding devices, it will be possible to invert the mercury and the electrolyte; the mercury may be held, by capillarity, in the tube, or tubes, whose dimensions shall have been modified if need be; for example, the coefficient characterizing the ν of progression of the inner section of the tube or tubes may be modified.

Figs. 4 and 5 represent embodiments of the upper part of the capillary tube in which the transmission of vibrations between the lower and the upper surface of the liquid 12 retained in the capillary tube 11, is effected through the medium of a thin diaphragm of suitable shape, resting on the upper surface of the liquid.

The devices shown, by way of example, Figs. 1, 2, 3, 4, 5 and 6, are reversible and may be utilized for transforming, as in the case of telephone receivers and loud speakers, varying electric currents into sound waves.

It will be noticed that the devices according to Figs. 1, 2, 3, 4, 5 and 6 may also be utilized to directly transform modulated high-frequency waves into sound waves, or operate a telephone receiver by means of the modulation frequency without there actually being electric detection of the high frequency. In this case, modulated high-frequency waves are directly transformed into sound waves. It is, indeed, known that the electrocapillary function of mercury whose surface is covered by an electrolyte may, upon first approximation, be rendered in the form

$$A = A_m - K(V_o - V)^2; \text{ (Helmholtz),}$$

A' being the value of the capillary constant for the potential difference V applied

between the mercury and the electrolyte and A_m , K and V_o being constants.

An alternative potential difference

$$U_{eff}\sqrt{2}$$

$\sin \omega t$ produces an average displacement of the level of the meniscus, contained in one capillary tube, proportional to the variation of the capillary constant $(\Delta A)_{alt} = -KU_{eff}^2$.

The potential difference actually applied in the immediate proximity of the contacting surface is not the total potential difference applied to the terminals of the device which may be represented diagrammatically by two resistances: one in series with the capacity of the contacting surface, the other in parallel therewith, representing the losses.

It will finally be noticed that if the electrolyte is constituted by sea water, the apparatus described may be directly utilized for submarine telegraphy and telephony for all sound and ultra-sound-wave frequencies without the use of any other medium.

It is moreover self-evident that the invention has only been described and represented here in a merely explanatory, but by no means limitary, manner and that it could be subjected to various modifications of detail without departing from the spirit thereof.

I claim:

1. Electrocapillary device adapted to be used either for the transformation of sound waves into electric currents, or conversely, or for the detection of electric oscillations, comprising in combination: a jar containing a good conducting liquid, a tube dipping, at its lower end, into said conducting liquid and containing an electrolyte the upper surface of which is substantially on a level with the upper edge of the tube and is free to vibrate, the inner section of this tube, which is capillary at the lower end, diverging towards the upper part according to an exponential law, and means for electrically connecting, to the external electric circuit, on the one hand, the conducting liquid, and, on the other hand, the electrolyte.

2. Electrocapillary device adapted to be used either for the transformation of sound waves into electric currents, or conversely, or for the detection of electric oscillations, comprising in combination: a jar containing a good conducting liquid, a tube dipping, at its lower end, into said conducting liquid and containing an electrolyte the upper surface of which is practically on a level with the upper edge of the tube and is free to vibrate, the inner section of this tube, which is capillary at the lower end, diverging towards the upper part according to an exponential law, a thin and projecting diaphragm resting on the upper surface of said electrolyte in order to improve the transmission of the vibrations between this upper

surface and the ambient air, and means for electrically connecting to the external electric circuit, on the one hand, the conducting liquid and, on the other hand, the electrolyte.

5 3. Electrocapillary device adapted to be used either for the transformation of sound waves into electric currents, or conversely, or for the detection of electric oscillations, comprising in combination: a jar containing a good conducting liquid, a tube of glass or other insulating substance containing an electrolyte the upper surface of which is practically on a level with the upper edge of the tube and is free to vibrate, the inner section of this tube, which is capillary at its lower end, diverging towards the upper part according to an exponential law and two conducting wires penetrating respectively without 10 in the conducting liquid and the electrolyte, and connected to the terminals of the external circuit.

4. Electrocapillary device adapted to be used either for the transformation of sound waves into electric currents, or conversely, or for the detection of electric oscillations, comprising in combination: a jar containing a good conducting liquid, a tube wholly or in a great measure metallic, dipping at its lower end in the conducting liquid and containing electrolyte the upper surface of which is free to vibrate, the inner section of this tube diverging towards the upper end according to an exponential law, a calibrated glass tube 15 fixed to the lower part of the metallic tube and the section of which is capillary and joins the inner section of the metallic tube, an insulating sheath surrounding the lower end of said metallic tube to isolate the same electrically from the conducting liquid, a conducting wire electrically connecting the conducting liquid to one of the terminals of the external circuit, and a conducting wire electrically connecting the metallic tube to 20 the other terminal of said circuit.

5. Electrocapillary device adapted to be used either for the transformation of sound waves into electric currents, or conversely, or for the detection of electric oscillations, comprising in combination: a jar containing a good conducting liquid, a tube wholly or in a great measure metallic, dipping at its lower end in the conducting liquid and containing an electrolyte the upper surface of which is free to vibrate, the inner section of this tube diverging towards the upper end according to an exponential law, a calibrated glass tube 25 fixed to the lower part of the metallic tube and the section of which is capillary and joins the inner section of the metallic tube, an insulating sheath surrounding the lower end of said metallic tube to isolate the same electrically from the conducting liquid, means for regulating the height of the metallic tube and in consequence, the calibrated

30 glass tube with regard to the level of the conducting liquid, a conducting wire electrically connecting the conducting liquid to one of the terminals of the external current, and a conducting wire electrically connecting the metallic tube to the other terminal of said circuit.

6. Electrocapillary device adapted to be used either for the transformation of sound waves into electric currents, or conversely, or for the detection of electric oscillations, comprising in combination: a jar containing mercury, a tube dipping, at its lower end, into said mercury and containing an acid or salt solution the upper surface of which is substantially on a level with the upper edge of the tube and is free to vibrate, the inner section of this tube, which is capillary at its lower end, diverging towards the upper part according to an exponential law, and means 35 for electrically connecting to the external electric circuit, on the one hand the mercury and, on the other hand, the acid or salt solution.

7. Electrocapillary device adapted to be used either for the transformation of sound waves into electric currents, or conversely, or for the detection of electric oscillations, comprising in combination: a jar containing an electrolyte, a tube dipping at its lower end into said electrolyte and containing a conducting liquid the upper surface of which is substantially on a level with the upper edge of the tube and is free to vibrate, the inner section of this tube, which is capillary at the lower end, diverging towards the upper part according to an exponential law, and means 40 for electrically connecting to the external electric circuit, on the one hand the conducting liquid and, on the other hand, the electrolyte.

8. Electrocapillary device adapted to be used either for the transformation of sound waves into electric currents, or conversely, or for the detection of electric oscillations, comprising in combination: a series of jars containing a good conducting liquid, a series of tubes dipping, each at its lower end, into said conducting liquid of one of said jars and containing an electrolyte the upper surface 45 of which is free to vibrate, the inner section of each of these tubes, capillary at the lower end and, diverging towards the upper part according to an exponential law, a conducting wire connecting the electrolyte of the first tube to one of the terminals of the external electric circuit, whereas another wire connects the conducting liquid from the last jar to the other terminal, and conducting wire connecting the conducting liquid of each jar 50 to the electrolyte of the tube dipping in the following jar.

9. Electrocapillary device adapted to be used either for the transformation of sound waves into electric currents, or conversely,

or for the detection of electric oscillations, comprising in combination: a jar containing a good conducting liquid, a series of tubes communicating through their upper parts and dipping each at its lower end, in said conducting liquid and containing an electrolyte the upper surface of which is free to vibrate, the inner surface of each of these tubes, capillary at the lower end, diverging towards the upper part according to an exponential law, means, such as an insulating sheath, for insulating, on the outside, each of the tubes of the conducting liquid, and means for connecting in parallel the electrolyte of each of said tubes to one of the terminals of the external circuit, the other terminal of which is connected to the conducting liquid.
